AGER FOR PROCESSING PRINTED FABRICS

Harry T. Prince, Warwick, and Waldo W. Smith, Warwick Neck, R. I., assignors, by mesne assignments, to Tower Iron Works Inc., Providence, R. I., a corporation of Rhode Island

Application November 29, 1952, Serial No. 323,202

3 Claims. (Cl. 68—5)

Although the art of printing piece goods is old and well-developed, as will appear by reference to the American Cotton Handbook (second edition, 1949), pages 650—689, considerable difficulties are still encountered when using vat dyes and the like materials which require steaming or aging for periods up to two hours. Recent developments in pad-steam dyeing using vat dyes and the like, have greatly increased the efficiency and reduced processing costs without materially sacrificing quality, but such developments are, as a practical matter, limited to plain shade work where bleeding does not present a problem. Attempts to extend such developments to printing piece goods with vat dyes and the like have been unsuccessful since the freshly printed goods tend to bleed and in traveling through a conventional steamer or ager the conveyor rolls pick up spread the different colors over the printed surfaces. Further difficulties are encountered in maintaining an oxygen-free atmosphere within the steamer or ager and in preventing injury to the goods by drippage as they enter, travel through and emerge from the ager.

The principal objects of the present invention are to overcome the aforementioned difficulties and to provide an improved process and apparatus for printing piece goods with vat dyes and the like material requiring aging or steaming.

More specific objects are to provide an improved ager or steaming apparatus in which an oxygen-free atmosphere can be maintained and in which injury to the goods by drippage as they enter, pass through and emerge, is avoided; and to provide an ager or steamer the design of which may be varied so as to accommodate the different layouts of finishing plants.

Further objects will be apparent from a consideration of the following description and the accompanying drawings, wherein:

Fig. 1 is a longitudinal view, partly in section, showing somewhat schematically an ager constructed in accordance with the present invention;

Fig. 2 is an enlarged section on the line 2—2 of Fig. 1;

Fig. 3 is a view similar to Fig. 1, but showing a second embodiment of the invention;

Fig. 4 is an enlarged section on the line 4—4 of Fig. 3.

Fig. 5 is a view similar to Fig. 1, but showing a third embodiment of the invention; and

Fig. 6 is a view similar to Fig. 1, but showing a fourth embodiment of the invention.

The term "vat dye" as herein used not only includes those dyes which are technically classified as vat colors, but also other coloring materials or dyestuffs the use of which requires successive treatments with a reducing agent and wet steam, followed by oxidation to develop color. The terms "aging" and "steaming" as used herein are synonymous, as are also the terms "ager" and "steamer."

In accordance with the present invention a fabric is pigment-padded on one face with a vat dyestuff in accordance with known procedures, and then chemical padded with a solution of a suitable reducing agent, the amount and precise nature of which is governed by the vat dye used

2

and the manufacturer's recommendations. Both the pigment padding and the chemical padding may be carried out in conventional equipment, as explained in the above-noted parts of the American Cotton Handbook to which reference may be had for a more detailed description of this part of the process.

Immediately upon emerging from the chemical padders the fabric is conducted through a chamber having an atmosphere of wet steam, free from oxygen, at a temperature between 212° F. and 220° F. for a period of from five seconds to thirty seconds or more, depending on the particular dye or dye mixture used; and during its travel through the steam chamber the fabric must only be supported at its opposite face, i. e., its non-printed surface. Thereafter the steamed-fabric is directly conducted to a washer where it is treated in conventional manner to develop color.

The successful practice of the process is dependent on the critical aging treatment which must be carried out so as to avoid the above-mentioned difficulties. To this end the ager should comprise a chamber having top, side and bottom walls of metal or other impervious sheet material, and entrance opening preferably closely adjacent to the chemical padder, and an exit opening preferably adjacent to and in line with the washer. Steam pipes associated with baffles or the like means are provided to introduce and distribute wet steam uniformly throughout the chamber.

A plurality of conveyor rolls is disposed within the chambers so as to define a path of travel for the fabric to be processed, the rolls being so arranged as to contact only the non-printed face of the fabric. In order to avoid condensation at any place where it would injure the fabric, a condensate-inhibiting panel or roof is disposed between the top or upper wall of the chamber and the conveyor rolls, the panel being of sheet metal or conductive material and coextensive with the length and breadth of the path of travel of the fabric through the chamber. Heating elements are disposed in the space between the panel and top wall in thermal contact with the panel so as to heat it by conduction and/or radiation to a temperature in excess of that at which condensation takes place. The outstanding advantages of having the heating elements within a housing defined by the panel and top wall are that as they do not come in contact with the wet steam or other processing fluid, they are not subject to corrosion, a more uniform distribution of heat is achieved, and where the heating elements comprise steam pipes, the development of a leak does not result in damage to the fabric under treatment.

The entrance opening of the chamber is provided with condensate conductors such as heated troughs effective to vaporize and/or conduct away condensate accumulating about the entrance. Similar means may be provided about the exit, but where, as is preferred, the exit is adjacent to and in line with the washer, the exit end may be provided with a duct through which the fabric travels, the end of the duct projecting below the water level of the washer so as to provide a seal preventing air from entering the chamber.

Since the printed fabric must at all times be supported at its undersurface, reverse travel or back and forth movement is prohibited, and hence the shape of the chamber, as defined by the path of travel of the fabric therethrough, is necessarily limited to non-linear paths, and generally U-, L- and J-shaped paths, as hereinafter described. Since the period of exposure is but a matter of seconds and as the rate of travel of the fabric may vary from 20 to 200 yards per minute, the shape of the chamber may be such as to allow the required period of exposure for any given plant layout.

Referring to Figs. 1 and 2, the embodiment shown

therein is designed for installation in a finishing plant where the floor space is such as to permit the pigment padder P, ager A and washer W to be set up on the same floor at substantially the same level. The padder P and washer W may be of conventional type respectively capable of printing and washing the fabric before and after passing through the ager A. Since the construction and mode of operation of pad-steam continuous dyeing apparatus are well known, reference to such literature as DuPont Bulletin E-959 and supplements thereto may be had for more complete disclosure and the same is true with wash boxes W where rinsing, oxidizing, soaping and rinsing successively take place.

The ager A comprises an elongate housing having top, side and bottom walls 1, 2, 3 and 4, preferably of stainless steel or the like corrosion-resisting material, which define the processing chamber 5. Mounted at spaced points along the outside walls 2 and 3 are brackets 7 which support pillow blocks or the like bearing members 8 in which the ends of shafts 9 supporting conveyor rolls 10 are journaled. The ends of the shafts 9 extend through fluid tight seals mounted in transversely aligned openings in the side walls, as illustrated in copending application, Serial No. 291,646 filed June 4, 1952. One end of each shaft carries a sprocket 12 or the like means by which the conveyor rolls are driven in synchronism. The relative position of the rolls is such as to define either a straight or a slightly arcuate path of travel through the chamber 5 and their length is such as to accommodate the width of the fabric F under treatment.

The entrance end of the chamber 5 is provided with a depending shield or closure plate 14, the lower edge of which carries a condensate-collecting trough 15 in which is disposed a steam pipe 16 for reducing or eliminating condensate which may collect in the trough, thus preventing condensate from dripping onto the printed face of the fabric F. Projecting upwardly from the lower side and bottom walls is a companion closure plate 18 the upper edge of which carries a steam pipe 20 spaced from the trough 15 a distance sufficient to permit the entrance of the fabric F into the chamber 5. A guide roll 22 is mounted exteriorly of the chamber 5 so as to guide the fabric F from the padder P through the slot or opening defined by the trough 15 and pipe 20. The opposite end of the chamber is provided with a closure plate 24, the lower end of which carries a trough 25 in which is disposed a steam pipe 26, the trough being spaced from the end of the bottom wall 4 so as to provide an exit opening 28 vertically aligned with the end conveyor roll 10.

Mounted above and approximately coextensive with the bottom wall 10 is a sheet metal floor 30, preferably of stainless steel, which provides an elongate shallow compartment 31 in which is disposed steam pipes or coils 32 in contact with the undersurface of the floor 30 so as to heat it by conduction and radiation, it being understood that the inner surface of the bottom wall 4 is preferably reflective so as to enhance the heating efficiency of the coils 32. Mounted above and coextensive with the floor 30 is a gable-like perforated baffle 34 which provides a steam-distributing housing or duct 35 through which runs a perforated steam pipe 36, the ends of the baffle 34 being closed by plates 38 and 39 so as to prevent steam from escaping through the ends of the duct. The lower ends of the plates 38 and 39 are integral with or joined to elongate transversely extending funnels 40 and 41 arranged so as to discharge condensate accumulating at the entrance and exit ends of the chamber 5.

Beneath the top wall is a condensate-inhibiting panel 45, preferably of stainless steel or the like sheet material, which provides an elongate compartment in which is disposed another set of steam coils contacting the inner face of the panel 45 so as to heat it by conduction and radiation, and here again the inner surface of the top wall is preferably reflective so as to increase the efficiency

of the heating coils 48. Access doors 50 are provided at spaced intervals along the side walls and the exterior of the chamber may be provided with a layer of suitable insulating material 52 so as to prevent heat losses and minimize condensation. In addition, conventional temperature controls (not shown) may be employed so as to insure uniform operating conditions.

In operation relatively high pressure steam is admitted to the steam pipes and coils 16, 20, 26, 32 and 48 so as to heat the chamber 5 and condensate troughs to a temperature above the condensation point (of the order of 212°-215° F.), and low pressure steam is admitted to the supply line 36 which discharges it into the compartment 35 where it passes through the openings in the baffle 34, as indicated in Fig. 2, thus providing a uniform atmosphere of wet steam at a pressure slightly above that of the outside atmosphere (of the order of a few inches of water) which is sufficient to prevent air from entering into the chamber through the entrance and exit openings. When the chamber is at the proper temperature the printed fabric F upon passing from the padder P is conducted over the guide roll 22 through the entrance slot with its printed surface spaced from the condensate trough 15 and into the chamber 5. The conveyor rolls 10, driven at a uniform speed, contact the undersurface of the fabric F and conduct it through the chamber 5 at a speed which provides the desired period of exposure. Although the coils 32 and 48 maintain the floor 30 and panel 45 at a temperature above that at which condensation normally takes place, nevertheless a slight amount of condensate may form on the side and end walls and also on the baffle 34, but the arrangement of the funnels 40-41 is such that any condensation so accumulating flows out through the funnels, thereby avoiding the danger of damaging the fabric under treatment. Likewise, condensate accumulating on the end walls 14 and 24 flows into the troughs 15 and 25 where it is either evaporated or conducted to a suitable drain. Due to the pressure in the chamber 5 there is a slight flow of steam outwardly through the exit and entrance openings but merely enough to prevent the entrance of air into the chamber.

Upon emerging from the chamber 5 the fabric F passes downwardly into the washer W where it is successively rinsed in hot water, neutralized with a sodium bicarbonate solution, soaped and again rinsed, which operations are conducted in the open air or oxidizing atmosphere to develop the color, after which the fabric is finished in conventional manner.

It will be noted that from the time the fabric leaves the padder P until it reaches the washer W its printed face does not come in contact with any parts which would cause the slightest bleeding of the color and by the time the fabric is conveyed to the washer W the coloring material is completely set.

The embodiment shown in Figs. 3 and 4 is the same in all material particulars as that shown in Figs. 1 and 2 and the same or similar reference characters are applied to corresponding parts. This particular embodiment is designed for installations where it is desired to conserve floor space and hence the ager A¹ is supported from the ceiling in any suitable manner with its entrance and exit above the padder P and washer W, respectively. The chamber 5^a is slightly arcuate as is also the path of travel therethrough defined by the rolls 10. The use of an imperforate floor above the bottom wall 4 is eliminated and a flat perforated baffle 34^a is used in place of the gable-like baffle 34 of the embodiment of Figs. 1 and 2, but otherwise the entrance and exit openings and associated parts hereinafter described are substantially the same.

The bottom wall 4^a adjacent to the entrance is formed with a transversely extending slot for the reception of the funnel 41^a which is positioned to receive condensate from the steam distributing duct 31^a, the ends of which are formed with openings, as shown in Fig. 3, and a sec-

ond slot outwardly of the funnel 41^a and in vertical alignment with the adjacent end roll 10 is formed in the bottom wall to provide the entrance opening 54. Communicating with the opening 54 is a vertically extending duct 55, preferably of stainless steel, shaped to accommodate the fabric F, and surrounding this conduit is a steam coil 56. A jacket 58 surrounds the coil 56 so as to provide a compartment functioning the same as the compartment 46, it being understood that the coil 56 is in contact with the outer surface of the conduit 55 and that the inner surface of the jacket 58 is preferably of reflective material.

The lower end of the jacket 58 terminates slightly above the upper rolls of the padder P, and the end portions are curved to provide a continuous trough 60 in which is disposed a heating pipe 61. The end of an inlet duct 62 is juxtaposed to the trough 60 and is connected to a suction fan (not shown) so as to draw steam or vapor away from these parts, as indicated by the arrow in Fig. 3. A layer of insulating material 64 covers the jacket 58 to prevent heat losses and minimize condensation.

The exit of the ager is of similar construction, the bottom wall 4^a having a slot to receive funnel 40^a and an opening communicating with a duct 65 surrounded by a coil 66 within a jacket 68 which is also covered with insulation 70. The lower ends of the jacket 68 and duct 65 are closed and these parts extend into the washer W below its normal water level so as to provide a seal preventing the entrance of air into the duct 65 and chamber 5^a.

Although the length of the chamber 5^a may be less than that of the chamber 5 of the embodiment of Figs. 1 and 2, the combined length of the chamber and associated ducts 55 and 65 may approximate that of the chamber 5 so that for the same rate of travel the fabric F is subjected to the same period of exposure. The operation is substantially the same as that above described, except that the fabric F travels along an inverted U-shaped path from the time it emerges from the padder to the time it enters the washer.

In the embodiment shown in Fig. 5 the ager A² is generally similar to that of Figs. 3 and 4, but is designed for installations in which the padding is done at one level and the washing and finishing at a lower level such as one or more floors below. In this embodiment the chamber 5^b and the path of travel therethrough approximates the shape of an inverted J and a condensate-inhibiting panel 70 is spaced inwardly of and is coextensive with the top or outer wall 1^b to provide a compartment for receiving the steam coils 48. In place of the longitudinally extending steam-distributing duct of the previously described embodiments, the steam distributor comprises a series of transversely extending perforated pipes 72, each provided with a semi-circular shield or baffle 74 which prevents jets of steam from impinging on the fabric F. The side walls carry a plurality of access doors 50^b, as well as the bearings for the conveyor rolls 10.

The entrance end of the chamber 5^b is closely adjacent to the upper rolls of the padder P and troughs 75, 76 and 77 are disposed about the entrance opening. Steam pipes 78 are disposed in these troughs and the inlet duct 79 of a suitable suction fan (not shown) is positioned so as to draw in vapor emerging from the inlet opening, as in the embodiment of Figs. 3 and 4. The bottom wall 4^b, inwardly of the entrance, is formed with an opening to receive the funnel 41^b which is arranged to discharge condensate accumulating on the bottom wall, thus preventing overloading of the trough 75. A layer of insulation 52^b covers the walls of the chamber 5^b, as in the previously described embodiments.

The exit end of the chamber 5^b is provided with a funnel-like duct or extension 80 which projects down-

wardly into the washer W to provide a seal preventing the entrance of air. The shape and inclination of the walls of the chamber 5^b are such as to eliminate the necessity of using a discharge funnel adjacent to the exit end, it being noted that the vertically extending portion of the bottom wall 4^b is such as to conduct condensate directly into the washer without danger of contacting the fabric F. Apart from the shape of the chamber 5^b the operation is the same as that of the embodiment of Figs. 3 and 4.

The embodiment shown in Fig. 6 is, in principle, the same as the previously described embodiments, but is designed to permit different periods of exposure without changing the rate of travel of the fabric through the processing chamber. In this embodiment the ager A³ comprises a housing of generally trapezoidal shape in longitudinal section, having an inverted U-shaped outer wall 91 adjoining side walls 92 and 93 and an inclined bottom wall 94. The side walls are provided with several groups of bearing members supporting conveyor rolls 10^a to 10^k, the arrangement being such that these rolls cooperate in defining a plurality of paths of travel of varying length through the chamber. One or more access doors 50^c are carried by the side walls as in the previously described embodiments.

Extending through the lower part of the chamber is a group of perforated steam distributing pipes 95, each provided with a perforated cylindrical baffle 96. Spaced inwardly of and coextensive with the outer wall 91 is a condensate-inhibiting panel 98 which provides a compartment for the steam coils 100. The lower end of panel 98 adjacent to the entrance opening joins a funnel 102 for carrying off condensate accumulating about this opening and the corresponding end of the panel adjacent to the exit adjoins a convergent duct 104, the lower end of which extends into the washer W below its normal liquid level to provide a seal, as in the previously described embodiments.

A duct 105 passes through the entrance opening and its inner end extends outwardly into the chamber beyond the adjacent steam distributor 95-96, terminating just below the roll 10^a. The lower end of the duct 105 is shaped to provide a trough 106 and is spaced above the upper rolls of the padder P, the construction and arrangement of parts being such that fabric F passing from the padder P travels through the duct 105 and contacts the rolls 10^a, 10^c and 10^h which are in substantial alignment. A heating coil 108 extends about the duct 104 and a corresponding heating coil 110 extends about the duct 104 and if desired insulation 52^c about the chamber may extend downwardly about the ducts 104 and 105.

The lower end of the bottom wall 94 is formed with a transversely extending slot or opening to receive the discharge funnel 112 so that all condensate accumulating thereon may be conducted to a suitable drain. In this embodiment, as in the previously described embodiments, the inner walls of the chamber are so arranged that condensate may flow either outwardly through the funnels 102 and 112 or through the duct 104 into the washer W.

It will be noted that the rolls 10^a-10^c define a relatively short path of travel through the chamber, as indicated by the dot and dash line; that the rolls 10^a, 10^d, 10^e and 10^c define a second path of travel, indicated by the dash line, which is of greater length than the first path; and the rolls 10^h-10^k define a third path of travel, indicated by the broken line, which is the greatest in length. Hence, without changing the speed of the padder, conveyor rolls and washer, a different period of exposure of the printed fabric may be obtained by selecting one of these paths of travel. A further feature of this particular design is that by eliminating the conveyor rolls 10^a and 10^c the fabric does not come in contact with any object before reaching conveyor roll 10^h at the upper part of the chamber and with certain types of coloring

material the time element in traveling from the padder to the roll 10^b is such as to permit the color to become set sufficiently to overcome the tendency to bleed or migrate. Hence, when using such coloring material both sides of the fabric may be printed.

While we have shown and described several embodiments of the invention, it is to be understood that this disclosure is for the purpose of illustration and that various changes and modifications may be made without departing from the spirit and scope of the invention as set forth in the appended claims.

We claim:

1. An ager for processing printed fabrics comprising an elongate chamber having top, side and bottom walls, said chamber having an entrance opening at one end and an exit opening at its opposite end, transversely extending conveyor roll means between the top and bottom walls of the chamber over which the fabric being processed is adapted to be drawn, entrance and exit guide means outside said chamber, said conveyor roll means and guide means being positioned with respect to said chamber to define a path of travel wherein only the non-printed face of the fabric being processed is contacted by said conveyor roll means as it is conducted through said chamber, means below said conveyor roll means for admitting and distributing a processing vapor, a condensate preventing means comprising a panel of corrosion-resistant sheet metal disposed between the top wall of said chamber and said conveyor roll means, said panel being substantially coextensive with the length and breadth of the path of travel through said chamber, and steam coils between said panel and top wall and in thermal contact with said panel so as to heat it by radiation and conduction.

2. An ager for processing printed fabrics comprising an elongate chamber having top, side and bottom walls, said chamber having an entrance opening at one end and an exit opening at its opposite end, transversely extending conveyor roll means between the top and bottom walls of the chamber over which the fabric being processed is adapted to be drawn, entrance guide means outside said chamber, exit guide means outside said chamber and disposed at a level below said exit opening, said conveyor roll means and guide means being positioned with respect to said chamber to define a non-linear path of travel wherein only the non-printed face of the fabric

being processed is contacted by said conveyor roll means as it is conducted through said chamber, means below said conveyor roll means for admitting and distributing a processing vapor, a condensate-preventing means comprising a panel of corrosion-resistant sheet metal disposed between the top wall of said chamber and said conveyor roll means, said panel being substantially coextensive with the length and breadth of the path of travel through said chamber, steam coils between said panel and top wall and in thermal contact with said panel so as to heat it by radiation and conduction, and condensate conductor means positioned adjacent the entrance opening for preventing drippage from striking the printed surface of the fabric.

3. An ager as set forth in claim 1, wherein certain of the conveyor roll means are disposed in groups at different levels within said chamber so as to define a plurality of paths of travel of varying lengths.
